UNITED STATES PATENT OFFICE.

EMIL H. ROSENBLATT, OF NEW YORK, N. Y.

DESIGN FOR A SPOON.

SPECIFICATION forming part of Design No. 22,032, dated December 6, 1892.

Application filed July 9, 1892. Serial No. 439,533. Term of patent 3½ years.

To all whom it may concern:

Be it known that I, EMIL H. ROSENBLATT, a citizen of the United States, residing at 237 East Seventy-second street, New York city, in 5 the county of New York and State of New York, have invented and produced a new and original Design for Spoons; and I do hereby declare the following to be a full, clear, and exact description of the invention, such as will 10 enable others skilled in the art to which it appertains to make and use the same, reference being had to the accompanying drawing, and to letters of reference marked thereon, which form a part of this specification.

15 The single figure of the drawing is deemed sufficient but necessary to illustrate my design.

20 The leading feature of the design consists in a spoon the bowl of which is waved in outline in imitation of the waves of the ocean; the wave-like configurations surrounding the figure of a steamship.

A in said drawing indicates the bowl of the

spoon, and B the handle thereof; a, the figure of a steamship upon the face of the bowl, and 25 b the figure or representation of the captain or naval officer. The spoon is also decorated with other ornamental figures pertaining to the sea, such as wave-shaped decorations c, which are displayed around the margin of the 30 bowl of the spoon, inclosing the figure of the steamship, rope-shaped decorations d, coral-like ornaments e, an anchor f, having seaweed g suspended therefrom, and a life-preserved h around the portrait or figure of said 35 naval officer.

What I claim as new is—

The design for a spoon herein shown and described.

In testimony that I claim the foregoing I 40 have hereunto set my hand this 23d day of May, 1892.

EMIL H. ROSENBLATT.
